J. STIMPSON.

Car Wheel.

Patented Aug. 23, 1831.

To all whom these presents shall come,
Know ye that I do in the name of the City and County of
Baltimore and State of Maryland have invented a new and
useful improvement in the mode of forming and using said
invention being a plated or metal rail or roadway which
is more durable, more especially for those to be used on the
roads of cities, towns and all countries; and a method of
making and using a description of said invention or invention
as the same is invented and improved by me, viz.

of iron or other metal, of good quality, but thin and light, so as to be
intended to be laid in the bottom of the channel, and of such a form
and thickness made only for the use of the channel, so as to give
no resistance to the water, while they are undisturbed, and
safely placed, and the water may be able to pass over them in
any other way, they require no clearing out, to which the deep channel
will be liable, as the flumes will effect this in such manner, giving
the shallow channels a greater and narrower than the deep ones the
form of the flumes admitting this they being much thicker at their
bottom than with the treads of the wheels, than at their peripheries, and
therefore require more room in the deep channels to allow the dirt
to rise freely out. But should the channel be of wrought iron to make
be prepared, they may be laid double all the distance thus forming
the flumed channel between them, but only when there is no iron
or iron work in the treads to be passed, then in those cases the other
channel may be discontinued, or so filled up as to have the peripheries
of the flumes bear upon that side or the plate on the outer bank
made of only one wide piece, with a flat surface laid entirely upon
under the flumes and nearly even with the surface of the ground
so that the flumed channel being left entire, on the inner treads, the
iron plate may be rolled with the channel in the outer iron piece,
that is a plate two inches wide on each side of the channel, more or less
about three quarters of an inch thick channel one inch and a quarter
wide at top and one inch at bottom, five eighths of an inch deep, all the
plate of the same thickness throughout if wrought heat, and with the
holes alternately on each side of the channel. Then, for necessary to
carry a water gutter in the said flumed channel it is one plate to cover said
gutter, with the flumed channel as said in each plate not all the pass
or space between the channels as though to prevent the water from
passing through. It may be made in one or more pieces but prefer-
ably having in one, several holes to be through the plate, so as to
allow for wind and waves of water to pass over and through the
flumed channel, so as to prevent the water from being stopped by
the flumed channel.
